US00D761865S

(12) **United States Design Patent**
Lee et al.

(10) **Patent No.:** US D761,865 S
(45) **Date of Patent:** ** Jul. 19, 2016

(54) **DISPLAY SCREEN OR PORTION THEREOF
WITH ICON**

(71) Applicant: **Samsung Electronics Co., Ltd.,**
Suwon-si (KR)

(72) Inventors: **Mi-Young Lee**, Seoul (KR); **Hyelin
Kim**, Seoul (KR)

(73) Assignee: **SAMSUNG ELECTRONICS CO.,
LTD. (KR)**

(**) Term: **14 Years**

(21) Appl. No.: **29/517,274**

(22) Filed: **Feb. 11, 2015**

(30) **Foreign Application Priority Data**

Aug. 29, 2014 (KR) 30-2014-0042304
(51) **LOC (10) Cl.** 14-04
(52) **U.S. Cl.**

USPC **D14/492**

(58) **Field of Classification Search**

USPC D14/485-495; D20/11
CPC G06F 3/04817; G06F 3/0482

(57) **CLAIM**

We claim, the ornamental design for a display screen or portion thereof with icon, as shown and described.

DESCRIPTION

FIG. 1 is a front view of a display screen or portion thereof with icon showing our new design; and,
FIG. 2 is a front view of another embodiment thereof.
The broken line showing of the display screen is for environmental purposes only and forms no part of the claimed design.

1 Claim, 2 Drawing Sheets

FIG. 1

FIG. 2
